B. Robert Werner

United States Patent Office.

B. ROBERT WEHNER, OF MANKATO, MINNESOTA.

Letters Patent No. 95,961, dated October 19, 1869.

IMPROVED EXCAVATOR.

The Schedule referred to in these Letters Patent and making part of the same.

To all whom it may concern:

Be it known that J. B. ROBERT WEHNER, of Mankato, in the county of Blue Earth, and State of Minnesota, have invented a new and improved Excavator; and I do hereby declare that the following is a full, clear, and exact description of the construction and operation of the same, reference being had to the accompanying drawings, making a part of this specification, in which—

Figure 1 is a front elevation;

Figure 2, a side elevation; and

Figure 3 is a plan view of a machine embracing my improvements.

This invention consists in making the central upright frame, on which is sustained the endless chain which carries the digging-apparatus, adjustable vertically, so that it may bear said apparatus as far down into the earth as it is desired to cut the ditch, and so that the bottom of the ditch may be perfectly plane; also, in mounting said frame upon a pivot, so that it may be turned down, when not in use, upon the truck which carries the machine, for convenience in transportation; also, in providing, in addition to the said central frame, side frames, armed with cutters and gutters, for forming the sides of the ditch, and conducting the removed earth to the central elevating-buckets, a reciprocating vertical motion being imparted to the said side frames, to enable them the better to perform their functions, and they being arranged so as to form the sides of the ditch at any desired inclination; also, in making the rear axle of the truck-frame extensible, so that the wheels may always run outside the ditch, however wide it may be at the top.

In the drawings—

A is the truck which carries the machine, which truck has three sets of wheels.

Between the middle and rear axles is placed the central frame B, which is made of two parallel side plates, b b, placed far enough apart to accommodate the elevating-chain, shovels, and scrapers between them, and each having a central longitudinal slot, b', fig. 1, reaching nearly its whole length.

These slots are intended to enable the frame B to slide up and down upon a stationary guide-frame, c, fig. 2.

The frame B rests upon a pair of small wheels, b" b", attached to the lower end of the frame by suitable arms, and these wheels run along the bottom of the newly-made ditch. The frame B slides freely upon its guide-frame c, and follows the ditch down without difficulty, to any required depth, and from this independence of the frame in its vertical movements with respect to the truck, it is evident that the former partakes of none of the irregular movements of the lat-

ter, caused by the unevenness of the surface, but cuts a perfectly plane bottom to the ditch, so that the water may all pass off without obstruction.

When the machine is *en route*, it is preferable that the frame B should rest nearly horizontally upon the truck.

To this end, the guide-frame c is pivoted in the metallic bars c' c', that connect the rear and central axles of the truck, and is held in an upright position by means of stay-rods, a a, which are screwed at their opposite ends to posts projecting upward from the rear end of the forward part of the truck. By unscrewing the stay-rods from the posts, the frames c and B may be turned down upon their pivot, and rest upon the forward part of the truck.

The endless chain which carries the shovels d and scrapers d', is made in the usual manner, by means of parallel rods, e, connected at their ends by links, e'. The shovels or picks are attached to the parallel rods, and have spear-heads, for the more easy rending of hard soil. The scrapers are placed alternately with the picks, being fastened to the side links.

The links pass over toothed wheels, h h', placed at the top and bottom of the frame B.

The pairs of wheels h h and h' h', are connected by means of shafts, h" h", and each shaft has a spur-gear on it between the toothed wheels.

A shaft, i, passes longitudinally through the frame B, connecting the two spur-gears, and driving them by means of pinions upon its ends.

The shaft i receives motion itself, by means of a spur-gear, k, placed upon it, and connected, by suitable belting and gearing, with the main driving-shaft l upon the forward part of the truck, which is impelled by steam, horse, or other power.

The earth taken up by the scrapers d' is discharged into a carrier-apron l', placed transversely on the rear part of the frame, and operated by means of a rod, l", connected at its forward end with the main driving-shaft l, and its rear end with the wheels on which the carrier-apron is mounted.

In the forward part of the truck, and connected with the main driving-shaft, is a windlass, m, around which is wound the rope that is fastened at its opposite extremity to a grapple, which, when the machine is in use, is carried forward to the length of its rope, and then firmly fastened in the ground. The action of the main driving-shaft will cause the windlass m to take up the rope and draw the machine forward. When it is desired to elevate the frame B out of the cut, this same rope may be detached from the grapple and fastened to the lower end of the frame, which will then be hoisted by the windlass.

In order to cut the sides of the ditch, I provide cutters, n", fastened along the outer edges of sheet-metal

plates, n , and inclined gutters, n' , with sharp cutting-edges, fastened along the front sides of said sheet-metal plates, which cutters form the sides of the ditch as the plates are moved up and down.

This motion is imparted to the plates by reason of their being attached to carriages o , one at each side of the central frame B , which carriages o slide on the outsides of guide-frames o' , the lower ends of which are pivoted to the lower ends of the sides of the central frame B , while their upper ends are attached to the outer extremities of arms o'' , the inner extremities of which are pivoted to the upper ends of the sides of the central frame, in such a manner that the said guide-frames o' may be fixed at a greater or less angle of inclination to the central frame, according to the slope it is desired to give the sides of the ditch, as shown in fig. 1.

The necessary motion is imparted to the carriages o , by cranks P , on the ends of short shafts in the lower part of the central frame, which cranks P are operated by connection with the gearing of the lower end of the central shaft i .

The cranks P are joined with the carriages o by connecting-rods Q , fig. 1. Thus, the side cutters play up and down as the machine progresses, and all the dirt they remove passes, by means of the gutters n' , to the scrapers d' ; and is by them removed. It is, of course, necessary to keep the wheels of the rear axle far enough apart to enable them to run always outside the ditch, whether it be cut wide or narrow. I therefore make the rear axle s , extensible, by forming it in two parts, and passing the inner ends of the parts

past each other through a pair of sockets, and fastening the parts of the axle in the sockets by means of set-screws, so that the axle may be extended at pleasure, as represented in fig. 4, which is a top view and transverse section of the axle, detached from the machine.

Having thus described my invention,

What I claim as new, and desire to secure by Letters Patent, is—

1. The central frame B , made vertically adjustable, so as to excavate a ditch with a plane bottom, and to any depth, and also so arranged, with reference to the truck A , as to be capable of being turned down horizontally for convenience in transportation, substantially as described.

2. Providing an excavating-machine with side-cutting apparatus, so arranged and made adjustable as to form a ditch with sides of any required slope, as and for the purpose set forth.

3. In combination with an excavating-machine having side-cutting apparatus, capable of receiving greater or less inclination, an extensible rear axle, arranged as and for the purpose explained.

4. Providing an excavating-machine with side-cutting apparatus, having a reciprocating motion, substantially as set forth.

To the above specification of my invention, I have set my hand, this 23d day of June, 1869.

B. ROBERT WEHNER.
